US00D777184S

(12) **United States Design Patent** (10) **Patent No.:** **US D777,184 S**
Yang et al. (45) **Date of Patent:** **** Jan. 24, 2017**

(54) **ELECTRONIC DEVICE WITH GRAPHICAL USER INTERFACE**

(71) **Applicant: TENCENT TECHNOLOGY (SHENZHEN) COMPANY LIMITED, Shenzhen, Guangdong (CN)**

(72) **Inventors: Guang Yang, Shenzhen (CN); Yu Yin, Shenzhen (CN); Yecheng Xian, Shenzhen (CN); Dazhi Yang, Shenzhen (CN); Dan Liu, Shenzhen (CN); Junbiao Chen, Shenzhen (CN); Yongyu Dai, Shenzhen (CN); Ruiyi Xiao, Shenzhen (CN); Yang Mo, Shenzhen (CN); Chao Hu, Shenzhen (CN); Yinglei Liang, Shenzhen (CN); Huiling Li, Shenzhen (CN); Wei Yan, Shenzhen (CN); Qinghua Zhong, Shenzhen (CN); Heming Shao, Shenzhen (CN)**

(73) **Assignee: Tencent Technology (Shenzhen) Company Limited, Shenzhen, Guangdong (CN)**

(**) **Term: 14 Years**

(21) **Appl. No.: 29/508,504**

(22) **Filed: Nov. 7, 2014**

(30) **Foreign Application Priority Data**

May 9, 2014 (CN) 201430126118

(57) **CLAIM**

The ornamental design for an electronic device with graphical user interface, as shown and described.

DESCRIPTION

The FIGURE is a front view of an electronic device with graphical user interface showing my new design.

The broken line showing of the electronic device are included for the purpose of illustrating environmental structure and form no part of the claimed design. The broken line showing of the display screen and portions of the graphical user interface are included for the purpose of illustrating portions of the article and form no part of the claimed design

1 Claim, 1 Drawing Sheet
